CLAIM

The ornamental design for a insulated food delivery carrier, as described and shown.

DESCRIPTION

FIG. 1 is a perspective view of the insulated food delivery carrier showing our new design;

FIG. 2 is a top plan view thereof;

FIG. 3 is a front elevational view thereof;

FIG. 4 is a left side elevational view thereof, the right side being a mirror image;

FIG. 5 is a left side elevational view thereof with the cover in an open position;

FIG. 6 is a rear elevational view thereof; and

FIG. 7 is a bottom plan view thereof.

FIG. 4

FIG. 5

FIG. 6

FIG. 7
